US00D753107S

(12) **United States Design Patent**
Magi

(10) **Patent No.:** **US D753,107 S**
(45) **Date of Patent:** **** Apr. 5, 2016**

(54) **WEARABLE COMPUTING DEVICE**

(71) Applicant: **Intel Corporation**, Santa Clara, CA (US)

(72) Inventor: **Aleksander Magi**, Aloha, OR (US)

(73) Assignee: **Intel Corporation**, Santa Clara, CA (US)

(**) Term: **14 Years**

(21) Appl. No.: **29/477,891**

(22) Filed: **Dec. 27, 2013**

(51) LOC (10) Cl. **14-02**

(52) U.S. Cl.

USPC **D14/344**; D11/23

(58) **Field of Classification Search**

USPC D2/627, 634, 635, 638, 978; D5/54;

D10/30, 32, 33, 38; D11/2, 4, 13, 23;

D14/344; 63/3

CPC ... A44C 5/0061; A44C 5/0069; A44C 5/0015

See application file for complete search history.

(57) **CLAIM**

The ornamental design for a wearable computing device, as shown and described.

DESCRIPTION

FIG. 1 is a perspective view illustrating a wearable computing device;

FIG. 2 is a back view illustrating a wearable computing device;

FIG. 3 is a front view illustrating a wearable computing device;

FIG. 4 is a side view illustrating a wearable computing device;

FIG. 5 is another side view illustrating a wearable computing device;

FIG. 6 is a top view illustrating a wearable computing device;

FIG. 7 is a bottom view illustrating a wearable computing device; and,

FIG. 8 is a perspective view illustrating a wearable computing device—shown in an alternate configuration of use.

In the drawings, the broken lines depict environmental subject matter only and form no part of the claim.

1 Claim, 3 Drawing Sheets
